REELING-MACHINE.

1,365,413.

Specification of Letters Patent. Patented Jan. 11, 1921.

Application filed November 1, 1917. Serial No. 199,643.

To all whom it may concern:

Be it known that we, FREDERIC S. KOCHENDORFER and HARRY BLOUNT, citizens of the United States, residing at Chicago, in the county of Cook and State of Illinois, and Oak Park, in the county of Cook and State of Illinois, respectively, have invented certain new and useful Improvements in Reeling-Machines, of which the following is

10 a full, clear, concise, and exact description.

This invention relates to a reeling machine, and more particularly to a reeling machine used for reeling or winding wire coated with an insulating covering of baked enamel on suitable receiving spools or reels.

15 The reeling machine is particularly adapted for use with the machine for coating wire illustrated and described in our co-pending application, Serial No. 179,479, filed July 20 9th, 1917.

One of the objects of this invention consists in the production of an improved reeling machine which will economize floor space and in which two reeling machine sections, 25 each comprising a plurality of reeling units, are driven by a single driving means.

Another object comprises the production of an improved capstan which is directly driven without slippage and which is provided with 30 means which prevents wire climbing and crossing and the consequent chipping of the insulating enamel coating on the wire which is being wound or reeled.

A further object resides in an improved 35 tripping mechanism which automatically stops the reeling units when the tension on the wire becomes excessive.

The invention is further characterized by an improved adjustable spool mounting 40 mechanism, by an improved wire tensioning means, by the general accessibility of the spools or reels and wire for purposes of inspection, and by various other features which will become apparent from the following description and the appended claims.

45 The invention is illustrated in the accompanying drawings, in which:

Figure 1 is a front elevation, partly in section, of the reeling machine with the central 50 portion of the machine broken away for the purpose of simplifying and reducing the size of the drawing;

Fig. 2 is an end elevation, partly in section, of the reeling machine;

Fig. 3 is a side elevation showing the 55 capstan and tripping mechanisms;

Fig. 4 is a front elevation thereof;

Fig. 5 is a section on the line 5—5 of Fig. 4 looking in the direction of the arrows and shows the tripping mechanism in its 60 normal position;

Fig. 6 is similar to Fig. 5 with the gearing and shafting removed and shows the mechanism in its tripped position;

Fig. 7 is a plan view of the reeling ma- 65 chine driving mechanism; and

Fig. 8 is a front elevation of the capstan illustrating the various angles utilized to prevent climbing and crossing of wires.

In the preferred form of the invention the 70 reeling machine consists of a plurality of reeling units grouped together on one frame, said units being used to draw the wire, at uniform speed, through the baking chambers of the machine illustrated in the above re- 75 ferred to co-pending application and to reel or wind the wire as it leaves the oven in substantially smooth layers on suitable spools or reels provided for this purpose.

Obviously the reeling machine herein de- 80 scribed can be used for other purposes by slightly modifying the detailed construction thereof, but in its form as herein described it is particularly useful, in combination with the machine for coating wire described in 85 our co-pending application, for the winding or reeling of wires which have been served with a coating of insulating enamel.

A complete reeling machine in its pre- 90 ferred form comprises 42 similar reeling units, of which but three complete units are shown in Fig. 1, the remaining units mounted on the central part of the machine having been broken away to simplify and reduce the size of the drawing. Each com- 95 plete reeling unit consists of a capstan device, a tripping mechanism, a friction take-up mechanism, a reel or spool support, a distributing mechanism and the necessary shafting and gearing for operating the same. 100

As illustrated in Figs. 1 and 2, the 42 units are mounted upon an I-shaped main frame 10, which frame is carried on suitable pedestals such as 11 arranged one at each end of the frame. The mounting pedestal at the left end of the machine is pro- 105 vided with an extension 12 which serves as a housing for the speed changing mecha-

nism interposed between the main vertical shaft 13 and the driving motor 14. As illustrated in Figs. 1 and 2, the reeling units are mounted on either side of the I-shaped 5 main frame and thus comprise two sections, one section being mounted on either side of the mounting frame, each section containing 21 reeling units, the 21 reeling units of each section receiving wire from a separate oven 10 which is placed opposite to each of these sections. This grouping of the sections on each side of the common mounting frame results in a very compact reeling machine which economizes floor space and which also 15 permits the use of one motor and a common driving mechanism to secure a driving means for the individual units of both sections mounted on either side of the frame.

As illustrated in Figs. 1 and 2, the capstan and tripping mechanisms, such as 15, 16, and 17, are mounted in a straight line across the top of the machine; while the spool or reel supporting means and the associated spools, such as 18, 19, and 20, are 25 staggered across the face of the machine in two rows, one row being located at the bottom part of the machine and the other about the center of the machine. The operating mechanisms of the various capstans and 30 tripping devices such as 15, 16, and 17, and the spool reeling mechanism proper, such as 18, 19, and 20, are all driven by suitable shafting and gearing from the main vertical shaft 13. The wire distributing device 35 24 and its associated and coöperating reversing mechanism 25 are likewise driven from this same shaft 13.

Since all of the 42 reeling units of the machine are identical, a description of one 40 of such units will suffice for the purpose of giving a clear understanding of the operation of the entire machine. Such a description of the capstan and tripping device immediately follows in connection with Figs. 45 3, 4, 5, 6 and 8.

The wire 26, after leaving the baking oven, is guided over the roller 27 to the guiding pulley 28, after which it is given two or three turns about the capstan 29 and 50 is then led over the guiding roller 30, from where it is led to a supply spool or reel such as 18, 19, or 20. The capstan and tripping mechanisms are driven from the main horizontal shaft 31 which, through suitable gearing, is driven from the main vertical shaft 13.

Secured to the main shaft 31 and associated with each reeling unit is a spur gear 32 which meshes with a spur gear 33 journaled on a short stud shaft 34 and which in turn meshes with the spur gear of the compound spur and bevel gear 35, the bevel gear of which meshes with the bevel gear 36 secured to the vertical shaft 37. The stud shaft 34 is mounted on a plate 38 which in

turn is mounted and pivoted at 39. The plate 38 carries at its front end a handle 40 and at its rear end a projecting lug 41 which rests against the mounting frame 10 when the plate 38 is turned about the pivot 39 to 70 its tripped position, as shown in Fig. 6. Secured to the upper part of the plate 38 by means of the screws 46 and 47 is a case hardened plate 48 which carries the projecting finger 49. 75

The plate 38 is pivotally secured to a bracket 50 which is secured to the main supporting frame 10 by screws 51 and 52. The bracket 50 carries a bearing 53 in which is journaled the shaft 31. Pivotally secured 80 to the bracket 50 by means of the screw 54 is a protruding arm 55. This arm is equipped at its rearward end with a protruding lug 56 in which is mounted by means of the screw 57 a case hardened latch 58 85 which coöperates with the finger 49 secured to the pivoted plate 38. The protruding arm 55 is fitted with an elongated slot 42 fitted with a plurality of arcuated depressions in which a cylindrical pin 59 rests. A 90 rod 60, carrying a weight 61, is secured to the pin 59. The pin 59 is held in position against lateral movement in the depressions of the slot 42 by means of a washer 43. The diameter of the pin 59 is considerably 95 smaller than the width of the slot, so that the pin can be moved from one depression to the next, whereby as the pin 59 is moved outwardly in the slot 42 the force required to raise the arm 55 about the pivot 54 will 100 increase.

It will be evident from Figs. 5 and 6 that when the handle 40 is raised, the plate 38 will pivot about the stud 39, the spur gear 33 rotating about the stud shaft 34 and in mesh with the spur gear section of the combination gear 35. As the plate 38 swings about the pivot 39 the finger 49 of the plate 48 rides along an inclined surface 62 of the latch 58, and the spur gear 33 is brought into mesh with the gear 32. When these gears are in mesh, the lower surface of the finger 49 will have been raised over the inclined top surface 63 of the latch 58, and the arm 55 turning about its pivot 54 will 110 slide the inclined surface 63 of the latch over the lower inclined surface of the finger 49 and lock the gears 32 and 33 in mesh, as illustrated in Fig. 5. When these gears are thus locked and swung into mesh, power 115 will be transmitted from the horizontal shaft 31 through this gearing to the bevel gear 36 attached to the vertical shaft 37 which carries at its upper end a bevel gear 64. The bevel gear 64 meshes with a bevel gear 65 secured to a shaft 66, at the other end of which a bevel gear 67 is secured. The bevel gear 67 in turn meshes with a bevel gear 68 which is secured to the capstan 29, the gear and capstan being journaled on 120 125 130

the stud shaft 70. Said stud shaft 70 is mounted in a forwardly extending bracket 71 secured to the upper part of the mounting frame 10.

- 5 The bracket 71 carries an upwardly extending lug 72 to which is pivotally secured by means of the screw 73 a rearwardly extending arm 74. This arm carries at its rear end a stud shaft 75 in which is journaled the wire guiding pulley 28. The arm 74 is also equipped with an upwardly extending lug 76 which carries the guiding roller 27. Protruding from the rear end of the arm 74 is a contact spring 77. This contact spring 77 rides under a rod 78 which is insulatively mounted on the top of the main mounting 10 by means of a plurality of rod mounting brackets such as 79. This rod constitutes one terminal of an alarm circuit, the other terminal of which is the grounded frame of the machine, these terminals being wired through a suitable battery to an alarm bell 80 mounted on the top of the machine and illustrated in Fig. 1.
- 25 The arm 74 which is pivoted at 73 is secured to the forwardly protruding arm 55 by means of a rod 81. This connecting rod 81 serves to raise the forwardly protruding arm 55 about its pivot 54 whenever the arm 30 74 is raised about its pivot 73. It will consequently be evident that when the tension on the wire 26 becomes sufficiently great to overcome the weight of the lever arms 74 and 55, the arm 74 will revolve about its pivot carrying with it the projecting arm 55, which in turn will unlatch the finger 49 and throw the gears 32 and 33 out of mesh, thereby removing the driving power of the capstan 29. The amount of tension in the 40 wire required to accomplish this action can be readily adjusted by shifting the adjusting weight in the arcuated depressions of the slot 42. These depressions have been numbered in pairs from 1 to 6 to facilitate 45 this adjustment. Obviously when the weight is hanging in the depression numbered 6 the tension required in the wire to release the finger 49 will be at a maximum, and this tension will be at a minimum when the 50 weight is hung from the depression numbered 1. Obviously any other suitable means for increasing the moment of the lever arm 55 can be utilized.
- In the reeling or spooling of wire which 55 has been served with a coating of baked insulating enamel it is very necessary to prevent scratching or scraping which will chip the enamel and cause bare spots in the wire. Great difficulty has been encountered in 60 signing a suitable capstan which will draw the wire through the baking oven and feed it to the reeling spool in a smooth, even manner without causing a certain amount of chipping and scratching. Obviously considerable power must be exerted by the capstan in drawing the wire through the oven; and unless crossing of the wire is prevented on the capstan in the various turns which are made about its surface for the purpose of increasing its drawing power, scraping 70 and scratching are bound to result.
- In the reeling machine as herein described this scraping has been substantially eliminated by a capstan which is directly driven from the source of power with suitable gearing and shafting and which is not subjected to slippage. In a direct driven capstan of this kind there is a tendency for the wire to pile up on the surface of the capstan, thereby causing crossings and subsequent scraping. This has been obviated in the present machine by the specially designed capstan illustrated in Fig. 8. Capstans are usually constructed with either an arcuated circumferential surface, or with a circumferential 80 surface having straight inclined sides and a flat bottom winding surface, or with a V-shaped circumferential surface. When capstans of these types are used for reeling wire there is a tendency for the wire to 90 climb up the curved or beveled inclined leading angular surface and finally to get to a high point from which it will start to slip down. In this slipping movement the oncoming wire will cross over the off-going 95 wire, and this will cause scraping of the enamel. This action will also produce considerable vibration of the wires in the baking oven, due to the slack introduced in the wire by this sudden wire slippage, and these 100 vibrations, as pointed out in our co-pending application, are exceedingly detrimental in the enamel baking operation.
- All of this difficulty has been overcome by the capstan illustrated in Fig. 8, in which 105 the bottom wire winding surface 86 of the capstan is given an angle of inclination, which angle is in the same general direction as the angle of the wire supplying side 87 of the capstan, but very much decreased in 110 slope. A very slight inclination of this wire winding surface in the general direction of the advance or leading angular surface will result in a satisfactory operation, but the most successful combination is the 115 one in which the leading or advance surface is given an angular inclination of 39 degrees from the vertical and the angle of the winding and pulling surface an inclination of 8 degrees from the horizontal. The other 120 side wall 88 of the capstan can be given any desired angular inclination, as the wire does not reach this wall of the capstan, but in the preferred embodiment herein illustrated is given an angle of 46 degrees from the vertical.
- The capstan is so located on the reeling machine that the oncoming wire from the guiding disk 28 will serve the same to the capstan on the advance guiding surface 87 130

at a point slightly above where this surface meets the bottom surface 86 of the capstan. The wire is preferably given two or three turns about this surface 86 of the capstan, 5 and due to the inclination of these two surfaces and this method of feeding the wire into the leading surface 87, the oncoming wire will always strike the leading surface and will gradually slide down to and along 10 the winding surface, from which it can be readily fed to the spool below. The angles of these surfaces substantially obviate all chances of climbing of the wire on the advance surface and of crosses between the 15 oncoming and the off-going wire.

From the capstan the wire is fed through a suitable guiding mechanism such as 89 secured to the cross bars 90 or 91 of the distributor, from which it is fed onto a reel 20 such as 18, 19, or 20. The wire is distributed across the reels by the reciprocation of the distributor cross bars 90 and 91 across the front of the machine. The amount of this lateral movement is controlled by the 25 reversing mechanism 25 which carries the lead screw 92 and to which is threaded the bracket 93 which is secured to the cross rods 90 and 91. As the screw 92 revolves, it carries with it the bracket 93 and this in turn 30 carries with it the cross rods 90 and 91. When a serving of wire has been fed to the spool the rotation of the screw 92 is reversed and the rods 91 and 92 return in the opposite direction to serve another layer of wire 35 to the spool. The preferred operation of the screw 92 and the controlling reversing mechanism is described in a co-pending application to James B. Kendall, Serial No. 148,214, filed Feb. 12, 1917, but it will be 40 obvious that any other well known reversing mechanism can be utilized for this purpose. The reversing mechanism and its associated apparatus is driven by a bevel gear 85 secured to the vertical shaft 13.

45 The spools or reels such as 18, 19, and 20 are supported on the main supporting frame 10 by means of a stationary bracket 94 and a movable bracket 95 (Figs. 1 and 2). The stationary bracket 94 is fitted with the bearings 96 and 97 in which is journaled a two-piece shaft 98 which is united by a friction drive 99. The part of the shaft 98 secured to the power end of the friction drive is connected to the vertical shaft 37 by means 50 of suitable bevel gears. The part of the two-piece shaft 98 secured to the other end of the friction drive terminates in a beveled gear which meshes with a corresponding gear secured to a disk which serves to rotate 55 the take-up reel or spool. The friction drive consists of a pair of plates in frictional contact, the plates being covered with either fiber, leather, cork, wood, or graphite, leather being used in the preferred form of 60 the invention.

The movable bracket 95 is mounted by means of a pin 100 in a channel 101 secured to the main mounting frame 10. The pin 100 is fitted with a spiral spring 102 which tends to hold the movable bracket 95 against the 70 take-up spool or reel and thus holds the spool against the driving element of the stationary shaft 94. Any suitable means for driving the spool from the rotating shaft attached to the bevel gear which meshes with 75 the bevel gear secured to the disk 98 may be utilized. In the preferred form of the invention the disk is fitted with a projecting pin which fits in a perforation with which the side walls of the spools are equipped. 80 To regulate the tension of the wire between the capstan 29 and the take-up spool an adjusting nut 103 is provided which is screw threaded on a protruding portion of the bearing 96. A spiral spring 104 is fitted between the outer face of the friction drive and said adjusting nut. Obviously as the adjusting nut 103 is turned so as to put the spiral spring 104 under compression, the friction 85 between the two faces of the friction drive 99 90 is increased, the outer face of the friction drive being slidably but rotatably mounted on this section of the two-piece shaft 98. As this friction increases, the force necessary 95 to cause slippage will correspondingly increase, and this will increase the tension in the wire between the capstan and the take-up spool. The tension of the wire between the capstan and the take-up spool can therefore be conveniently regulated by the adjustment nut 103, which in turn determines 100 the degree of tightness with which the wire is wound on the spool. As the wire 26 is fed to the take-up spool at a certain determined and definite rate, depending upon the diameter of the capstan and its rate of rotation, the wire must be wound on the take-up spool at the rate at which it is fed to said spool by the capstan. When the wire is first wound 105 on the spool—that is, when the core is small, the spool will rotate at approximately the same rate as the capstan, and there will be a little slippage between the opposing faces of the friction drive. However, as the body of this core increases in diameter, the angular 110 speed of the take-up spool must be correspondingly decreased.

115 As hereinbefore stated, the operating parts of the reeling machine are driven from a vertical shaft 13, one for each reeling machine section—that is, one on each side of the mounting plate 10. These shafts are driven from the motor 14 through a speed changing device interposed therebetween which is illustrated in Figs. 1 and 7. As there shown, 120 the shaft of the motor is equipped with a spur gear 110 which meshes with another spur gear 111 mounted on a shaft 112. The shaft 112 carries a second smaller spur gear 113 which drives a gear 114 mounted on a 125 130

shaft journaled in the bearing 115, to the other end of which is secured a spur gear 116. The spur gear 116 meshes with spur gear 117 mounted on a shaft 118 with fourteen other spur gears, each one of a different diameter. The shaft 118 is journaled in the bearings 119 and 120. It will consequently be obvious that as the motor shaft revolves, motion is transmitted through the spur gears 110, 112, 113, 114, and 116 to 117 which rotate the shaft 118, and likewise the remaining fourteen spur gears rigidly secured to said shaft.

Directly above the shaft 118, to the right and left, are mounted two separate shafts 121 and 122. Mounted on each of these shafts is a slidable housing such as 123 which carries an upwardly extending rod 124, on the extreme end of which is mounted a handle 125. The housing 123 carries between its two downwardly extending arms 126 and 127 a pinion 128 slidably mounted on the shafts such as 121 and 122 by means of the key and key-way 129. The pinion 128 is in mesh with an intermediate gear 130 which is carried on a stud shaft 131, the shaft being journaled in a bearing secured to a projecting arm 132 which is integral with the housing or shifter 123. The intermediate gear 130 may be rotated about the pinion 128 into mesh with any of the spur gears mounted on the shaft 118, as the pinion 128 and its associated housing are shifted or slid to and fro on the shafts 121 and 122.

The top 133 of the housing 12, which encloses the speed changing device, is fitted with a plurality of lateral slots such as 134 in alignment with the series of spur gears on the shaft 118, the lateral slots terminating in a longitudinal slot in which the upwardly extending rod 124 of the shifting device extends and which permits longitudinal movement of the shifter or housing.

It will be evident from the above that when the handle 125 is moved toward the center of the machine, the intermediate gear 130 will be rotated out of mesh with its associated spur gear on the shaft 118, due to the rotation of the shifter or housing 123 on the shafts 121 and 122. The longitudinal slot in the housing is given an angle of inclination from the horizontal which corresponds to the angle of the side of a cone formed by the gradual increasing sizes of the spur gears mounted on the shaft 118. Due to this angle of inclination of the slot in the housing, the distance that the intermediate gear 130 must be rotated to draw it out of mesh, from its associated spur gear, and permit its shifting longitudinally from one spur gear to another is always the same. Thus for a very slight lateral movement of either handle 125, the shifters 123 are free to slide along either shaft 121 or 122, and intermediate gears may be brought into mesh with

any of the fifteen spur gears on the shaft 118. Consequently fifteen changes of speed may be secured for either shaft 121 or 122 by shifting the handles 125.

The shafts 121 and 122 terminate respectively in the bevel gears 135 and 136 and these bevel gears mesh respectively with the bevel gears 137 and 138, which are rigidly secured to the main vertical shafts 13 which transmit power through appropriate gearing to the horizontal shaft 31, which in turn supplies power to the individual reeling units. Since the shifters 123 associated with the shafts 121 and 122 are independent of one another and can be adjusted independently, and inasmuch as the spur gears on the shaft 118 serve as a common drive for the intermediate gears 130 and the pinions 129 which drive the shafts 121 and 122, both sides of the gear changing mechanism are utilized for driving purposes. This results in a marked economy without sacrificing or reducing to any extent whatsoever the flexibility of the driving mechanism.

In the operation of the reeling machine the wire or any other material which it is desired to reel or wind is first fed to the guiding roller 27, around the guiding pulley or wheel 28, after which it is given several turns about the capstan 29 from where it is fed over the guiding roller 30 and thence through the guiding rollers of the distributor 89 to the take-up spool or reel. The motor 14 having been started, the handle 125 of the gear shifting device is moved to the notch which will give the desired speed. This will rotate the cross shafts such as 121 or 122 which in turn, through the bevel gearing at the end of said shafts, will rotate the main vertical shaft 13. The main vertical shaft, through its associated bevel gear 85, will rotate the screw 92 of the distributor and operate the associated reversing mechanism 25. Power from the shaft 13 will also be transmitted to the horizontal power shaft 31 to which each of the reeling units may be connected by operation of the handle 40 of the tripping device. As the wire is strung in each unit, this tripping device is operated, which transmits power through suitable gearing, hereinbefore described, to the shaft 37 and thence to the capstan 29 and the take-up reel. The position of the rod 60 and the consequent movement of the tripping arm is determined for each size of wire and said rod is properly set in the slot 42 before the tripping device is operated. The rotation of the capstan will draw the wire from the oven or any other suitable supply means and the rotation of the take-up reel in combination with the reciprocations of the distributor will lay the wire in smooth, even layers on the take-up reel. If for any reason difficulty is encountered in the supply means so that the ten-

sion in the wire 26 becomes excessive the tripping mechanism will be actuated, as hereinbefore described, which will immediately stop the rotation of the shaft 37 and consequently the capstan 29 as well as the supply reel. When the tripping mechanism of any unit is operated, the spring 77 makes contact with the rod 78 which will close the serial circuit from ground through a battery, the vibrating bell 80, the rod 78, and the spring 77 to the frame of the reeling machine and back to ground. The ringing of the alarm bell will inform the operator that one of the tripping mechanisms has been operated, which mechanism can be readily located by the operator because of the inclination from the horizontal of the handle 40, as illustrated in Fig. 6. The operator will then locate the trouble in the wire supplying means, and when this is removed the tripping device is returned to its operating position, as shown in Fig. 5.

The reeling machine as hereinbefore described is exceedingly beneficial and useful in the reeling and coiling of baked enamel wire, the reeling operation being performed with substantially no injury whatever to the enamel covering with which the wire has been served. This together with the compact manner in which the plurality of reeling units are assembled and the positive operation of the tripping device when trouble in the wire supply manifests itself makes the operation of this machine very efficient and economical. The use of this machine results in a further economy because of the small amount of floor space required per reeling unit.

The invention is obviously not limited to the specific embodiment herein illustrated and described, but is capable of many other applications with but slight variations without departing from its spirit and scope as set forth in the following claims.

45 What is claimed is:

1. In a device of the character described, in combination, a capstan, a reel to receive the material to be wound, means to rotate said reel and capstan, and a mechanical trip mechanism operable to disengage said means from said reel and capstan when the tension on the material drawn by said capstan exceeds a specified limit.

2. In a machine for reeling wire, in combination, a capstan, a reel to receive the oncoming wire, a common driving means for said reel and capstan, means to regulate the tension of the wire between said reel and capstan, and means comprising an angular relationship between the winding and pulling surfaces of said capstan whereby climbing and crossing of the wire on the capstan is prevented.

3. In a device of the character described, in combination, a capstan, a reel to receive

the material to be wound, means to rotate said reel and capstan, a mechanical tripping mechanism operable to disengage said means from said reel and capstan when the tension of the material that is being wound by said capstan exceeds a specified limit, and means to regulate the force required to actuate said tripping mechanism.

4. In a machine for reeling wire, in combination, a capstan, means to guide the wire to said capstan, a pivotal support for said means, a wire receiving reel, means to rotate said capstan and reel, and means operated by said pivotal support to disengage said capstan and reel from said rotating means whenever the tension of the oncoming wire becomes excessive.

5. In a reeling machine, in combination, a capstan, a reel, a driving means, means interconnecting said means and said reel and capstan to rotate the same, and a pivotally mounted guiding means operated to disengage said reel and capstan from said driving means whenever the tension of the oncoming wire becomes excessive.

6. In a wire reeling machine, in combination, a capstan, a receiving reel, a wire guiding means which guides the wire to said capstan, a pivotal support for said guiding means, means for rotating said reel and capstan, a driving means, means operable to interconnect said driving means with said reel and capstan rotating means, and means interconnecting said last mentioned means with said pivotal support to automatically disengage said reel and capstan rotating means from said driving means whenever the tension of the oncoming wire to be reeled becomes excessive.

7. In a wire tension controlling mechanism for a reeling machine, the combination with a capstan and a receiving reel, of means for rotating said reel and capstan, a driving means operable to interconnect said rotating and driving means, and means comprising a pivotally supported wire guiding means automatically operated to disengage said driving and rotating means when the tension of the oncoming wire becomes excessive.

8. In a wire tension controlling mechanism for a reeling machine, the combination with a capstan and a wire reeling machine, of means comprising gears and shafting to rotate said reel and capstan, a driving means comprising a driving shaft and gear, a gear pivotally supported and operable to rotate about said driving gear to interconnect it with said reel and capstan rotating means, and means automatically operated to disengage said interconnecting gear from said rotating means.

9. In a machine for reeling wire, the combination with a capstan, of a wire receiving reel, means to rotate said reel and cap-

stan, and means associated with said reel rotating means to regulate the tension of the wire between said capstan and reel.

10. In a machine for reeling wire, the combination with a capstan, of a wire receiving reel, a common driving means to rotate said reel and capstan, a friction drive for rotating said reel, and means to adjust said friction drive to regulate the tension of 10 the wire between said capstan and reel.

11. In a machine for reeling wire, a plurality of reeling units comprising two sections, a mounting means carrying one of 15 said sections on each side thereof, a driving means for each section, a power driving shaft, a common means interconnecting said

sectional driving means and said power driving shaft whereby the same or different speeds may be simultaneously transmitted to the sectional driving means, means 20 to connect each individual unit with its associated sectional driving means and means comprising an adjustably weighted latch adapted to be automatically operated to disconnect a unit when the tension of the on- 25 coming wire becomes excessive.

In witness whereof we hereunto subscribe our names this 17th day of October, A. D., 1917.

FREDERIC S. KOCHENDORFER.
HARRY BLOUNT.
